UNITED STATES PATENT OFFICE.

JOHN R. SUMAN, OF HOUSTON, TEXAS.

ROTARY EARTH-BORING DRILL.

1,388,490.

Specification of Letters Patent. Patented Aug. 23, 1921.

Application filed September 18, 1920. Serial No. 411,180.

To all whom it may concern:

Be it known that I, JOHN R. SUMAN, a citizen of the United States, residing at Houston, Harris county, Texas, have invented 5 a certain new and useful Improvement in Rotary Earth-Boring Drills, of which the following is a full, clear, and exact description, such as will enable others skilled in the art to which it appertains to make and use 10 the same.

My invention relates to an improvement in drills for boring in earth, rock, or other similar formations in the digging of wells for water, oil, gas, etc.

15 My drill is designed as a combination bit for use in material of different degrees of hardness. It is an object of my invention to design a drill for well digging which is adapted to work in different characters of 20 formation and to cut the strata evenly and with a minimum amount of vibration.

Another object is to provide a tool of this character having cutting means which are easily removable and replaceable when 25 worn.

Another object is to provide a device of this character which will have means to discharge the flushing fluid at numerous points upon the surface being cut and in such manner as to wash the material directed from 30 the cutting points. Other objects and advantages will appear from the description which follows:

Referring to the drawing, wherein like 35 numerals of reference are applied to like parts throughout the several views, Figure 1 is a central longitudinal section through a drill bit embodying my invention, taken on the line 1—1 of Fig. 2; Fig. 2 is a bottom 40 plan view of my invention; Fig. 3 is a central longitudinal section of a broken portion of the bit showing one of the cutting teeth and its method of attachment; Fig. 4 is a top plan view of one of the cutting teeth; and 45 Fig. 5 is a view showing a modified means of attaching the cutting teeth to the bit.

In the drawing I have illustrated the preferred embodiment of my invention, in which I have a head 1, somewhat cup-shaped 50 in construction, and having the upper open end thereof threaded at 3 for attachment to a drill stem 2. The cutting teeth 4 of my drill project radially from the outer surface

of the cup-shaped head so as to present the appearance of a flattened hemisphere with 55 peg-shaped projections covering the outer surface thereof.

The cutting teeth are practically cylindrical in shape intermediate their ends, the outer cutting portion being beveled, as 60 shown particularly in Fig. 3, the beveled portion being curved inwardly and then downwardly so as to present a sharp cutting edge 5 to the material. A central water channel 6 extends longitudinally of the 65 tooth so as to discharge the flushing fluid at the lower portion of the cutting face. As the teeth project radially from the center of the bit, the teeth extending laterally, as shown at 7 in Fig. 1, perform the larger part 70 of the cutting action with the lower edge of the cutting face and, to allow for this fact, the cutting face is wider toward the lower portion of these teeth than at the upper portion, as will be noted in Fig. 1. The teeth 75 are secured in position by having the inner end 8 enlarged somewhat and fitted within a recess 9, shaped to receive the same on the inner face of the head 1. The recess 9, and the enlarged portion 8 fitting therein, are 80 shaped somewhat oval, as shown in Fig. 4, so as to prevent rotation of the cutting tooth when fitted in position.

To retain the teeth in operative position when they have been placed within the head, 85 I provide a cup-shaped retaining member 10, spaced to fit closely against the inner face of the head 1 so as to bear against the inner ends of the teeth and hold them securely within their seats. This retaining member 90 is in turn held in position by the screwing of the head 1 upon the drill stem 2, the drill stem 2 having a shoulder 11 at the lower end adapted to bear upon the upper edge of the retaining member 10. Dowel 95 pins 12 are preferably fixed within the lower inner face of the head 1, projecting inwardly, so that when the retaining member 10 is fitted in position these dowel pins will fit within openings 13, formed to register 100 with the said dowel pins and receive the same. In the central portion of the outer face of the head 1, I have formed a threaded recess 14, into which I screw a specially formed tooth or pilot bit 15, the said tooth 105 being flattened in the manner of a fish tail

bit and pointed so as to form a pilot member adapted to center and guide the bit and also to cut away efficiently the material at the center of the hole. Two central channels 16 5 for flushing water are provided longitudinally of this cutting tooth so as to efficiently clear the same of material.

As will be noted from Fig. 1, the teeth fitting against the rounded outer face of the 10 cup-shaped retaining member 10 do not conform to the shape of the retaining member and in order to remedy this I contemplate providing washers 17, as shown in Fig. 3, which are perforated to provide a channel 15 18, registering with the channel in the tooth and having the inner face concaved to fit against the outer face of the retaining member. These washers may be of somewhat compressible material, in which case they 20 will not have to be specially formed, or they may be made of hard material, in which case I contemplate forming the same with concaved inner faces, conforming with the shape of the retaining member. In Fig. 5, 25 I have shown a different means of attaching the cutting teeth within the head. In this embodiment, the inner end is threaded at 19 for attachment within the head, it being contemplated that the teeth will be screwed 30 firmly within the head until the cutting face is directed in the proper position for cutting.

The flushing water for the bit is pumped 35 downwardly through the hollow drill stem and through holes 20 in the retaining member and the channels 6 in the teeth so as to be projected directly against the cutting faces thereof. As will be seen, it is possible to form the holes 20 in the retaining member 40 to register with the downwardly directed cutting teeth and to omit such openings in the upper rows of teeth, which are directed laterally, it being contemplated that the flushing water, directed toward the forward 45 cutting edge, will be sufficient to wash these teeth which perform the larger part of the cutting action, and to also flush away the cuttings from the upper teeth. It is obvious, however, that if desired openings 20 may be 50 formed to register with the ends of the cutting teeth at the sides of the head also.

When the teeth are fitted in position, the recesses 9, into which the heads 8 of the cutting teeth fit, will be formed in such manner 55 that the teeth will present the cutting face in a direction radial from the center of the bit and directed forwardly in the direction of rotation of the bit so as to bring the cutting edge 5 into contact with the material 60 in the most efficient manner. Thus when the bit is rotated the teeth 4 will act upon the material at the bottom of the hole and act to disintegrate the material so that it may be washed away by streams of flushing water 65 pumped downwardly through the bit and

through the channels in the cutting teeth, so as to wash the cutting edge thereof and to carry the material in suspension upwardly outside of the drill to the surface of the ground. In case any of the cutting teeth become dulled, it will be possible to quickly unscrew the head, remove the retaining member and substitute new teeth for the dulled or broken teeth, and proceed with the drilling. This form of drill will be easy to repair and 70 smooth and efficient in its action and will not be liable to become balled up by material clogging thereabout.

Having thus described my invention, what I claim as new and desire to protect by Letters Patent is:

1. A rotary earth boring drill comprising a head, radially projecting teeth on the outer face thereof, said teeth having cutting edges presented forwardly in the direction of rotation and means to discharge flushing water against the cutting edges of each of said teeth.

2. A rotary earth boring drill comprising a cup-shaped head, teeth projecting radially from the forward end of said head, an enlarged inner end on each of said teeth fitting within recesses on the inner face of said head and a retaining member bearing against said inner ends.

3. A rotary earth boring drill comprising a cup-shaped head, teeth projecting radially from the outer face of said head, means to retain said teeth non-rotatably in position, and means to flush the cutting material from each of said teeth.

4. A rotary earth boring drill comprising in combination, a hollow drill stem, a cup-shaped head thereon, peg-shaped teeth projecting radially from said head, and means to retain said teeth in fixed position in said head, said teeth having sharp cutting edges presented in the direction of movement thereof.

5. A rotary earth-boring drill comprising the combination of a drill stem, a cup-shaped head secured thereon, cutting teeth projecting outwardly from said head, and a cup-shaped retaining means lining the inside of said head, said retaining means being held in fixed position against said teeth by the lower end of said drill stem.

6. A rotary earth boring drill comprising the combination of a drill stem, a cup-shaped head secured thereon, cutting teeth projecting through said head, a retaining means fitting closely against the inner face of said head, said retaining member, head and teeth having registered channels to conduct flushing water onto the cutting points of said teeth.

7. A rotary earth boring drill comprising a hollow head, teeth projecting radially therefrom in forward and lateral directions, said teeth having oval shaped inner heads

thereon fitting in oval recesses in said head and means to retain said teeth in position.

8. A rotary earth-boring drill comprising a hollow head, and radially projecting teeth mounted removably in said head, said teeth having the lower ends beveled to present forward sharp cutting edges to the work,

and having flushing channels to discharge fluid from within said head upon the cutting faces thereof.

In testimony whereof I hereunto affix my signature, this the 14th day of September, A. D. 1920.

JOHN R. SUMAN.
